UNITED STATES PATENT OFFICE.

AUGUSTE NAMUR, OF NEW YORK, N. Y., ASSIGNOR TO THE TUTTLE & BAILEY
MANUFACTURING COMPANY, OF SAME PLACE.

DESIGN FOR A BORDER-FRAME FOR REGISTERS.

SPECIFICATION forming part of Design No. 15,916, dated March 3, 1885.

Application filed January 8, 1885. Term of patent 14 years.

To all whom it may concern:

Be it known that I, AUGUSTE NAMUR, a citizen of Luxemburg, Germany, residing at New York city, in the county and State of New York, have invented and produced a new and original Design for Border-Frames for Hot-Air Registers, of which the following is a specification.

The accompanying photographic print represents my new and original design for border-frames for hot-air registers in front elevation.

The design consists of the line of bead or dot figures *a*, between the plain ribs *b*, along each margin of the bars of the frame, together with the corner squares *c*, and with stipple or dead finish *d* between the corners *c*, the

said corners *c* inclosing the quadrifoliate figures *e*.

I claim—

The design for border-frames for hot-air registers herein shown and described, the same consisting of the line of bead or dot figures *a*, between the plain ribs *b*, along each margin of the bars of the frame, together with the corner squares *c*, quadrifoliate figures *e*, inclosed in said squares, and the ground *d*, as herein set forth.

In witness whereof I have hereunto signed my name in the presence of two subscribing witnesses.

AUGUSTE NAMUR.

Witnesses:
